[57] CLAIM

The ornamental design for a rod retainer or similar article, as shown and described.

DESCRIPTION

FIG. 1 is a left side, top and front perspective view of a rod retainer or similar article, showing our new design; FIG. 2 is a left side elevational view thereof, with a rod retained therewithin relative to a panel, and with the rod and panel shown in broken lines for illustrative purposes only, and forming no part of the claimed design;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and, FIG. 8 is a cross-sectional view taken in the direction of the arrows on line 8—8 of FIG. 5.

FIG. 1

FIG. 3
